CLAIM

The ornamental design for a heel for footwear as shown and described.

DESCRIPTION

FIG. 1 is a front perspective view of a heel for footwear showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top view thereof; and,

FIG. 7 is a bottom view thereof.

(Continued)

The broken lines in the drawings represent environmental matter that forms no part of the claimed design.
